UNITED STATES PATENT OFFICE

ANTHONY B. OBIDZINSKI, OF PITTSBURGH, PENNSYLVANIA, ASSIGNOR OF ONE-FOURTH TO JACOB GOLDSTEIN AND ONE-FOURTH TO JOSEPH J. GOLDSTEIN, BOTH OF PITTSBURGH, PENNSYLVANIA

SAFETY APPARATUS FOR SUBMARINE VESSELS

Application filed March 20, 1928. Serial No. 263,048.

This invention relates to safety apparatus for submarine vessels, more particularly to means for furnishing aid to a submarine crew in distress, as the result of accident.

It is among the objects of this invention to provide means positive in its action for signalling the location of a disabled submarine which shall be provided with means for communicating to the crew inside of the disabled vessel.

Another object of the invention is to provide means for effecting connection with the interior of a submarine vessel to enable a rescue party to furnish sustenance and an adequate supply of fresh air to the submarine crew.

Another object of the invention is to provide means for obtaining the objects set forth above by the use of apparatus of simple construction which may be designed to function for the purposes stated in a positive and efficient manner and which shall be manipulated from the interior of the submarine vessel without any possibility of endangering the lives of the crew.

These and other objects will become more apparent from a consideration of the accompanying drawings in which like reference characters designate like parts and in which Fig. 1 is a diagrammatic view illustrating an embodiment of the invention in its practical form and in accordance with the principles thereof; Fig. 2 is a sectional view of a compartment provided in the submarine vessel showing the position of the buoy cable and the communicating tube arranged in a manner to be hereinafter explained. Fig. 3 is a similar view of the compartment with the outer wall closed showing the position of the buoy. Fig. 4 is a front elevational view thereof with the outer wall cut away. Fig. 5 is a cross-sectional view of the signalling buoy. Fig. 6 is a carrier or shell employed for transmitting supplies to the crew of the submarine through a supply tube, a fragmentary portion of which is shown in Fig. 7. And Figs. 8 and 9 are transverse and longitudinal sectional views of the supply tube taken along transverse and longitudinal lines through the joint of the tube.

Referring to the figures of the drawings, the structure therein illustrated comprises a submarine 1, a rescue vessel 2, the latter being moored by an anchor 3. The submarine 1 is provided with compartments generally designated at 4 which are located at some convenient and accessible place on the submarine hulk, preferably the mid section thereof where they will produce a minimum interference with the location of machinery and working space on the interior of the submarine.

The compartment 4 is more clearly illustrated in connection with Figs. 2, 3 and 4 of the drawings and is formed with its end walls 5 continuous with the hulk 6 of the vessel, thus rendering the compartment waterproof. A side wall or cover 7 is hinged at 8 adjacent the lower end of the compartment and is adapted to open the compartment at 70 the top. The cover 7 is provided with a gear rack 9 of segment shape, the teeth of which co-act with the thread 10 of a worm screw which is actuated by the shaft 11 from the interior of the submarine vessel through the well known form of hand-wheel 12 or by motive power. The section of the compartment wall through which the shaft 11 projects is preferably provided with enlarged portions 13 and 14 to provide a suitable bearing surface and also to provide for a packing joint in which a packing gland 15 is secured by a gland nut 16 to prevent leakage from the compartment to the interior of the vessel, this being further augmented through a shoulder 17 on the worm shaft 11.

It is clear from a description of the gear mechanism that the outer cover 7 can be opened to its full extent regardless of external pressure caused by the location of the vessel at any given depth, and it is further evident from the construction that the cover need only be opened slightly depending upon the tilt of the hulk before the detrimental pressure is exerted into a useful one to aid in opening the cover after the segment has entirely passed from its engagement with the worm 10.

As is clearly shown in Figs. 2 and 3, a partition member 18 made to curve outwardly

at its upper portion, is secured in the compartment in any suitable manner and a buoy generally designated at 19 is disposed within the compartment and released without any further application of force upon the opening of the hinged outer wall in the manner explained. The buoy 19 is connected at 20 to a flexible cable 21 which is anchored in the compartment at 22. The buoy 19 may be 10 provided with a glass dome or top 24, Fig. 5, secured in a substantial manner as by a screw ring 25 to the lower portion of the buoy and the interior of the buoy may be provided with a reflector 26 and a lamp socket 27 for receiving a lamp 28. The lamp socket 27 is provided with an electrical connection 29 which runs through the flexible cable 21. The electric light 28 can be energized from a suitable source of electrical energy such as a battery 30 or dynamo provided for that purpose in the interior of the submarine vessel.

The cable 21 is preferably secured to a projecting hub portion 30 of the buoy by means of a lead bushing 31 to assure a secure 25 and unbreakable connection therewith and the buoy is further provided with a recess 32 normally closed by a screw thread plug 33 that can be removed by a wrench or otherwise for the purpose of gaining access to a 30 socket 34 of telephone line 35 which extends through the cable 21 to the interior of the submarine. The electrical conduits 29—35 of the light and telephone respectively are extended through the bottom wall of the compartment 4 as shown in Fig. 2.

After the submarine has been located by means of the buoy 19, it is of course necessary and desirable to provide means for supplying the submarine crew with fresh air and food 40 or perhaps medical supplies. This can be effected in the following manner:—

A nipple 37 is disposed through an opening 38 formed in the bottom of the compartment 4 or if preferred, the nipple may be formed 45 integrally with the bottom wall. In the construction shown in Fig. 3, the nipple 37 is provided with a flange 39 which is secured to the wall of the compartment by a weld 40 around the periphery of the flange. The ends 50 of the nipple are provided with caps 41—42 which are secured by screw threads 43 or in any other suitable manner to render them water proof and removable. The nipple is utilized by attaching at the upper end a tubular member 45 which consists of suitable 55 lengths of flexible tubing connected by joints generally designated at 46. The tube is lowered from the vessel 2 as shown in Fig. 1 and fastened to the nipple 37 by a diver. 60 When the cap 42 is removed, the cap 41 is retained on the nipple to prevent the flow of water to the interior of the vessel. After the connection has been effected in the proper manner, the submarine crew is notified 65 through the telephone line extending from

the buoy that such connection has been made and the lower cap 41 is subsequently removed. Food and supplies may then be conducted through the tube to the crew inside the submarine and this may conveniently be accomplished by the use of a carrier 48, Fig. 6 which comprises a sleeve or shell having end caps 49 and 50 secured thereto as by screw threads 51. The end caps are provided with eyes 52 and hooks 53 whereby a series of such carriers may be joined and passed through the tube simultaneously. The caps 49 may be employed as drinking cups and both liquid and solid foods may be placed in the carrier. 70

On account of the stress to which the conduit 45 is subjected by the action of the waves and relative movement of the vessel 2 and submarine 1, it is desirable to form the same of flexible material and to further relieve the conduit of stress produced in the manner set forth, I provide a plurality of reinforcing members in the form of cable 55 which may be secured to the periphery of the flexible conduit at its joints 46. 80

For this purpose the joint is constructed in 90 the manner illustrated in Figs. 8 and 9 in which the cable 45 is shown as provided with metal bushings 56 and 57, the member 56 having a screw thread 58 and the member 57 having a flange 59 which forms a shoulder 95 for a screw sleeve 60 which is provided with a threaded area adapted to interact with the thread 58 to effect an interlocked joint of the ends of tubes 45. The screw sleeve 60 is preferably provided with slots 61, Fig. 8, 100 adapted to receive the reinforcing cable members 55 which are disposed above the periphery of the tube and held in place by a ring 63 which is in threaded engagement at 64 with the ring 60. It will be apparent that 105 the sections of the tube 45 can be speedily assembled on board the rescue ship 2 and the reinforcing cable 55 secured thereto by means of the joint shown in Figs. 8 and 9, and that such construction will protect the 110 tube against any material strains.

The operation of the apparatus described above is briefly as follows: Normally, the buoy secured to the cable 21 carrying the electric light and telephone lines is disposed in the compartment 4 in the manner illustrated in Figs. 3 and 4; with the outer wall 7 secured to close the compartment, water is excluded from the chamber to prevent deterioration of the mechanism and parts contained therein. 115

When the submarine becomes disabled through injury by collision or incapacitation of its means of locomotion, the compartment is opened by manipulating the hand wheel 12 from the interior of the submarine to throw back the cover 7 and the buoy 19 is immediately released and rises to the surface as illustrated in Fig. 1. Any surface vessel 120 casually in the vicinity will be attracted by 130

the signal such as the light of the buoy or smoke or reflections, any one of which may be employed, the crew of such vessel can immediately communicate with the crew of the submarine by telephone through the plug contained on the buoy, it being assumed, of course, that if apparatus of the nature of my invention were adopted for the purpose, that coast vessels would be provided with necessary equipment to effect such communication. By thus establishing connections, the condition of the submarine and its crew can be readily ascertained.

Subsequently, when the services of a diver are available, the supply tube 45 may be connected to the nipple 37 in the manner explained and both air and food and other supplies can be furnished the submarine crew.

It will be evident from the foregoing description of this invention that it is especially designed to provide simple and practical means for accomplishing the objects therein stated with the greatest facility and dispatch and with the least possibility of failure in the manipulation of the apparatus.

The present invention does not contemplate any means for rescuing the crew from a submerged vessel or for salvaging the vessel itself, and is particularly designed as an emergency measure to enable a submarine crew to survive until a rescue can be effected.

Although one embodiment of my invention has been herein illustrated and described, it will be obvious to those skilled in the art that various modifications may be made in the details of construction without departing from the principles herein set forth.

I claim herein as my invention:

1. In a submarine, a compartment having its end walls continuous with the hull of the vessel, and having its outer wall hinged at the side of the vessel to open at the top edge of the compartment, a buoy mounted in said compartment and adapted to be released by the opening of the said hinged wall, said buoy being permanently anchored to the vessel, a sloping guide provided at the top of said compartment for directing the movement of said buoy out of said compartment and means operative from within the submarine vessel for moving said hinged wall to its open position.

2. In a submarine, a compartment having a hinged wall in alignment with the side of the hull, a nipple secured in said compartment and projecting into the interior of the submarine, and a tube adapted to be fastened to the end of the nipple within said compartment, said tube having flexible cable disposed along the longitudinal axis thereof and joined at intervals to the tube to reinforce the same and to relieve it of lateral stresses.

3. A submarine structure as set forth in claim 2 in which the tube is formed in lengths

joined at their ends and in which the flexible cable is fastened to the tube at its connecting joints.

In testimony whereof, I have hereunto set my hand.

ANTHONY B. OBIDZINSKI.
